Earle L. Grindle.
J. H. McCready,
his attorney.

UNITED STATES PATENT OFFICE.

EARLE LINWOOD GRINDLE, OF ELLSWORTH, MAINE.

MARINE ENGINE.

Application filed November 2, 1926. Serial No. 145,780.

This invention relates to internal combustion engines intended more especially for marine use, and it has for its general object to provide highly efficient engine of this 5 type at a substantial reduction in cost.

The demand for marine engines has not been such as to warrant their manufacture on a large scale and with the special equipment which is used in manufacturing many of the 10 standard automobile engines. In other words, the advantages of mass production are not available to the user of a marine engine. The result is that a purchaser of a marine engine today is obliged to pay considerably 15 more for engines of moderate horse power than is charged for automobile engines of the same power. It is, therefore, an important object of this invention to so modify a standard automobile engine that it will be entirely 20 satisfactory for marine use.

The invention will be herein disclosed in connection with the well known Ford automobile engine which is both inexpensive and efficient. The invention makes it possible to 25 convert this engine at a comparatively small expense into an efficient marine engine, the total expense, including the initial cost of the engine and the expense for modification, being very substantially less than the expense 30 for a marine engine of equal efficiency and power.

The nature of the invention will be readily understood from the following description when read in connection with the accompanying 35 drawings, and the novel features will be particularly pointed out in the appended claims.

In the accompanying drawings,

Figure 1 is a plan view of a portion of a 40 Ford engine modified in accordance with this invention;

Fig. 2 is a side elevation of the construction shown in Fig. 1;

Fig. 3 is a longitudinal, cross-sectional view 45 of the mechanism, certain parts being shown in elevation;

Fig. 4 is a transverse, cross-sectional view 50 of part of the mechanism shown in Fig. 3; and

Fig. 5 is a diagrammatic view illustrating 55 the planetary gearing hereinafter described.

In the drawings, 1 represents the crank shaft of the engine and 2 the propeller shaft. Fast on the crank shaft 1 is the usual fly wheel 3 carrying, as usual, three compound or triple planetary pinions 4, 4, 4, Figs. 3, 4 and 5.

The standard Ford automobile engine includes a transmission mechanism through which the crank shaft 1 drives the propeller shaft 2. This mechanism comprises the set 60 of triple pinions 4, 4, 4 above referred to, and also a reversing drum, a low speed drum and a brake drum. As is well understood by those familiar with these engines, these three drums are provided with sleeves telescopically fitting one within the other, said sleeves being provided at their forward ends with pinions, each meshing with one of the pinions of each triple pinion 4. When the engine is driving 65 full speed ahead the crank and propeller shafts are connected together through a clutch and the three drums and the planetary pinions all rotate idly around the axis of the crank shaft, there being no motion of the planetary pinions on their own axes. By releasing the clutch and stopping the rotation 70 of the reversing drum, the planetary pinions are caused to roll on the pinion at the end of the sleeve of the reversing drum, and thereby 75 they are caused to reversely rotate the brake drum and propeller shaft. Or, if the rotation of the low speed drum is stopped while the clutch is out, then the planetary pinions roll around upon the gear on the sleeve of 80 said low speed drum so that the brake drum and propeller shaft are caused to lag, but travel in a forward direction at a slower speed than the crank shaft. Stopping the rotation 85 of the brake drum stops the rotation of the propeller shaft for the reason that this drum is rigidly connected with the propeller shaft. 90

Thus in the ordinary Ford automobile motor or power plant there are two speeds ahead and one reverse speed. The slow forward speed is of no use for marine purposes, 95 and the reverse speed is too slow. The present invention, by making simple changes in the engine, overcomes these objections. It also provides a simpler control mechanism.

In modifying a Ford automobile engine to 100 provide a marine engine in accordance with my invention, the brake drum 5 and the low speed drum 6 are made into one unit which may be done by welding the same together as indicated at 7, Fig. 3, of the drawings. The two brake mechanisms (not shown) cooperating 105 with these drums in the ordinary Ford transmission are dispensed with, and the usual pinion (not shown) at the forward end of the brake drum sleeve 8, which in the standard Ford transmission cooperates with the pinion members 4^a of the planetary pinions 110

4, is removed. The usual brake lever is dispensed with and in place of its shaft a fixed stop stud 9 is substituted. Instead of the usual shaft and lever for operating the brake on the slow speed drum 6 a fixed stub shaft 10 and control lever 11 are used, the latter being connected by an adjustable link 12 with an arm 13 fast on the shaft 14 of the brake mechanism for the reversing drum 15.

10 The sleeve 16 of the low speed drum 6 is, as usual, provided at its forward end with gear teeth 17 in mesh with the intermediate members 4^b of the planetary pinions, while the sleeve 18 of the reversing drum 15 is provided at its forward end with gear teeth 19 meshing with the rear pinions 4^c of the planetary pinions. The usual clutch located inside the brake drum 5 is retained and includes a set of friction disks 20 which are keyed to 20 the brake drum or driven member 5, as usual, these disks cooperating with another set of friction disks 21 keyed to the periphery of a clutch drum or driving member 22 which is keyed to the crank shaft 1 of the engine. 25 Bearing against the clutch disks is a pressure ring 23 provided with studs, one of which is shown at 24, that project through holes in a flange or member 25 having a hub that is rigidly fixed to the propeller shaft 2. The 30 flange 25 is fastened, as usual, by screws 26 to the rear end of the drum 5 and carries a series of radially disposed levers, one of which is shown at 27. These levers are fulcrumed at 28 on the flange 25 and have their 35 inner ends cooperatively disposed with relation to the forward end of a sleeve 29 slidably mounted upon the propeller shaft 2. The sleeve 29 is provided with an annular groove to receive studs 31 projecting from a 40 yoke 30 which is mounted on a rock shaft 33. At one end the rock shaft extends through the wall of the housing, Figs. 1 and 2, and a lever 34 is secured thereto. The control lever 11 is provided with a cam arm 11^a having an 45 elevated dwell portion 11^b concentric with the axis of the stud 10 and a receding portion, or drop, 11^c. This cam arm acts on an adjustable screw 35 carried by one of the arms of the lever 34. A spring 36, Fig. 3, mounted 50 between the sleeve 29 and an abutment collar 43 acts through the levers 27 to set the clutch or hold it "in", and this spring also yieldingly urges the screw 35 of the lever 34 toward the cam 11^a.

55 When the control lever 11 is thrown forward to the limit of its movement, as indicated by dot and dash lines, Fig. 2, the drop 11^c of the cam passes beyond the screw 35, and the spring 36, acting through the connections just described, sets the clutch. At this time, therefore, the crank shaft of the engine 1 and the propeller shaft 2 will be connected together through the clutch and they will revolve in unison. This is the condition for 60 full speed forward.

The ordinary Ford engine transmission includes a brake band 38, Fig. 4, extending around the reverse drum 15, the ends of said band being punched to receive the shaft 14. A spring 40 tends to expand the band. The arm 13, above mentioned, is secured to the outer end of the shaft 14 and this arm is provided with a hub having cam lugs 41 co-operating with cam lugs 42 on the engine housing. As the control lever 11 is thrown 75 into its forward position it acts through the link 12 and the arm 13 to rock the shaft 14 in a direction to cause the cam lugs 41 to ride down on the lugs 42, thus permitting the spring 40 to shift the shaft 14 endwise and 80 expand the brake band 38 so as to free it from the reversing drum 15. When the control lever 11 is shifted from its forward position, Fig. 2, to its "reverse" position, as shown in full lines, the cam lugs 41 and 42 will 85 co-operate to force the shaft 14 outwardly, thereby contracting the brake band 38 on the reverse drum 15 and stopping the rotation of the latter. This causes the pinions 4^c to roll 90 on the gear teeth 19 at the forward end of the sleeve 11 of the reverse drum 15, thus rotating the triple pinions on their own axes and causing the pinions 4^b to act through the gear teeth 17, sleeve 16, and the unified drums 6 and 5 to drive the propeller shaft 2 in its 95 reverse direction. As the control lever 11 is thus shifted from its forward position to its reverse position, the cam arm 11^a acts through the screw 35, lever 34, rock shaft 33, arms 32, yoke 30, sleeve 29, and levers 27, to 100 release or throw out the clutch, and it is maintained in this condition while the engine is in reverse.

The parts are so constructed that there is an intermediate or neutral position of the 105 control lever 11 (indicated by dotted lines in Fig. 2) in which the screw 35 still remains in engagement with the elevated dwell 11^b of the cam 11^a so that the clutch is held out, and the cam lugs 41 of arm 13 lie between 110 the cam lugs 42, Fig. 4, with the shaft 14 at the limit of its inward movement and the reverse drum 15 free. Consequently, in this neutral position of the control lever 11 the clutch is released and the reverse drum is 115 free so that the propeller shaft 2 is not then driven in either direction.

It will thus be evident that when the changes above described have been completed the engine has a single speed forward 120 and a single reverse speed. The entire operation of the transmission is under the control of a single lever 11. Due to the fact that the reverse speed is produced through the pinions 4^c and 4^b meshing, respectively, with the gear teeth 19 and 17, a much higher reverse speed is obtained than in the standard Ford construction, the gear ratio in reverse giving approximately 96% of the forward speed. 130

Thus by making the relatively simple changes above described an engine is produced which is admirably adapted for marine work. Due to the fact that Ford engines 5 are manufactured in very large quantities and with the aid of much special equipment, the present invention makes it entirely possible to buy a new engine and adapt it for marine use at an expense which shows a very substantial 10 saving when compared with the cost of a new marine engine delivering the same power.

While I have herein shown and described the best embodiment of my invention that I have so far devised, it will be understood that 15 the invention is not limited to embodiment in the precise form shown.

Having thus described my invention, what I desire to claim as new is:

1. In a marine engine, the combination 20 with a crank shaft, a fly wheel thereon and a propeller shaft, of a set of compound planetary pinions rotatably mounted on said fly wheel; a clutch including a driving member fast on said crank shaft and a driven member 25 connected with said propeller shaft, said driven member being provided with a gear meshing with one member of each of said

planetary pinions; a reverse drive drum loosely supported by said crank shaft and provided with a gear meshing with other 30 members of said planetary pinions; a brake mechanism for said drum; an operating shaft for said clutch, a lever connected with said brake mechanism to operate it, a cam arranged to be operated by said lever, and 35 connections between said cam and clutch shaft whereby said lever controls the operation of the clutch.

2. In a Ford automobile engine wherein the 40 brake mechanisms for the brake and low speed drums are dispensed with and said drums fastened rigidly together, and wherein the usual gear on the brake drum sleeve is dispensed with, the combination with the 45 brake mechanism for the reverse drum of the engine and the operating mechanism for the clutch, of a single control lever connected with the brake mechanism for the reverse drum and provided with a cam for actuating the clutch operating mechanism, said cam 50 having portions being shaped to hold the clutch out when said lever is in either its neutral or reverse positions.

EARLE LINWOOD GRINDLE.
